CLAIM

The ornamental design for a display screen or portion thereof with graphical user interface, as shown and described.

DESCRIPTION

FIG. 1 is a front view of a display screen or portion thereof with graphical user interface; and

FIG. 2 is a front view of a second embodiment thereof; and, FIG. 3 is a front view of a third embodiment thereof.

The outermost broken line rectangle showing a display screen or portion thereof forms no part of the claimed design. The remaining broken lines showing text and portions of the graphical user interface form no part of the claimed design.

1 Claim, 3 Drawing Sheets
